RESYNCHRONIZING SYSTEM FOR
CONTROLLERS

Carl H. Bissell, Syracuse, N. Y., assignor to
Crouse-Hinds Company, Syracuse, N. Y., a
corporation of New York

Application January 21, 1931. Serial No. 510,223

10 Claims. (Cl. 172—293)

This invention relates to resynchronizing systems which include a plurality of controllers, each controller including a cycle timer, and actuating means therefor, and has for its object, 5 a particularly simple means for synchronizing or resynchronizing the timers at predetermined intervals, as once during each cycle of operation of the timers, which means includes switches connected in series in a resynchronizing circuit, one 10 switch for each timer, and means operated by the current in the resynchronizing circuit when all of the switches are closed for again starting the timers simultaneously on their next cycle of movement and preventing overlapping of the operation of the stopping means and the starting means, by delaying the closing of circuits which control the stopping of the controllers until after 15 the timers have had time to be actuated far enough in their next cycles to prevent the closing 20 of the circuit by the stopping means until the timers have again completed their cycles.

The invention consists in the novel features and in the combinations and constructions hereinafter set forth and claimed.

25 In describing this invention, reference is had to the accompanying drawings in which like characters designate corresponding parts in all the views.

Figure 1 is a diagrammatic view of a system 30 of street intersections to which this invention is applicable.

Figure 2 is a schematic diagram of the system. 35 This system, although applicable to any systems embodying a plurality of timers which must run in substantial synchronism, is especially adapted for highway traffic signaling systems, wherein the signals at a plurality of points or intersections pass through repeated traffic cycles from go to stop on one highway or street, to stop 40 to go on an intersecting highway or street, and back to go on the first street, and stop on the second street.

1 designates the main street. 2, 3, 4 and 5 are intersecting streets.

45 The signals are arranged at each intersection, and each intersection is provided with a controller.

6 designates a controller located at the central station, and including any mechanism common to 50 all of the controllers 7, 8, 9 and 10 located at each intersection, as for instance, the relay switch and the thermal switch to be hereinafter described.

55 This resynchronizing system comprises generally a plurality of controllers, each comprising a

cycle timer, and actuating means therefor, means controlled by each timer for stopping the same at the end of its cycle independently of the other timers, timed means common to all of the controllers and controlled by the last stopped timer 60 for starting all the timers simultaneously on their next cycles, and cutting out the stopping means until the timers have had time to progress far enough on their next cycles to themselves cut out the stopping means until the end 65 of the next cycle. The cycle referred to herein is the cycle of the timer, and not the traffic cycle, or the cycle of the signals.

Usually the timer cycle and the traffic cycle are the same, that is, the timer makes one revolution 70 during each traffic cycle, or change of signals from go to stop on one street, stop to go on the other, and back to go on the first street, and stop on the second street. It will be understood however, that the resynchronizing opera- 75 tion may take place once during each traffic cycle, or once during a plurality of traffic cycles.

11 designates the controllers for the intersections, two of such timers being shown.

13 designates the shaft of the timer and the 80 actuating means for the timer is usually an electric motor 14, the motor being usually of induction disk type. The cams for timing the operation of the signals are omitted. They are mounted on the timer shaft 13, and as the opera- 85 tion of the cams form no part of this invention, and as their operation is well understood, further illustration and description is thought to be unnecessary. It will be understood that during the rotation of the shaft 13, the signals at the intersection controlled by any one timer pass through 90 a traffic cycle from go to stop on one street, and from stop to go on the intersecting street, and back to go on the first street, and stop on the intersecting street. 95

The means controlled by each timer for stopping the same independently of the other timers as here shown, comprises two coacting parts, one being fixed from movement with the timer, and the other movable with the timer.

100 15 designates the fixed part, which is here shown as pivoted at 16 to any fixed point as the frame of the timer, and movable on its pivot against the action of a returning spring 17. 18 is the other of said parts, this being actuated by 105 the timer shaft 13, and usually, and preferably, mounted on or connected to the shaft 13 to rotate at the same speed therewith so that it operates or coacts with the part 15 once during each rotation of the timer shaft 13. This part 18 is 110

usually called the offset arm. It is carried by a disk 19 on the timer shaft and adjustable into different radial angles about the shaft 13 and held in its adjusted positions in any suitable manner. The handles 20, 22 and 23, shown in the drawings, are for the purpose of adjusting the timing cams not shown, and form no part of this invention.

In the illustrated embodiment of my invention, 10 the timers are stopped at predetermined intervals by stopping or stalling the motor, and the motors are stopped by energizing bucking coils 25 which act in opposition to the driving coils 26 to completely oppose the same at predetermined intervals, and these bucking coils are connectible in the feed circuit at predetermined intervals in order to entirely oppose the driving coils and stall the motors. The bucking coils are 15 also normally connected in the feed circuit through a voltage regulator or reducer in order to normally partly oppose the driving coils, and as the voltage regulator is adjustable to vary the voltage, the speed of the motors can be varied by adjusting the voltage regulator. The bucking coils are 20 25 in effect, merely means for stopping the motors and for normally applying a predetermined braking force less than the driving force to the motors.

The manner of adjusting the speed of the 30 motors forms no part of this invention, and the speed of the motors may be varied in any suitable manner, as for instance, varying the voltage through the starting coils.

In the illustrated embodiment of my invention, 35 the driving coils 26 are connected independently of each other in the feed circuit, or a local circuit and the driving effect of the driving coils of each motor is assumed to be the same and constant. The circuits in which the bucking coils are 40 connected are as follows:

30 and 31 designate respectively the feed wires. 32 is a wire connecting the wire 30 to one side of the voltage regulator 33. 34 is a wire leading from the voltage regulator 33 and having a branch 35 connected to one terminal 36 of a switch 37, the terminal 36 coacting with and normally engaging a companion terminal 38 which is connected by a wire 39 to one end of the bucking coil of the companion motor, the other end of the bucking coil being connected by a wire 40 to a common return wire 41 which is connected to the feed wire 31. There are branch wires 39 and switch 37 for each timer. Thus, normally the bucking coils are energized by a current cut 50 down by the voltage regulator and hence, apply a retarding force for the motor 14 less than the force applied by the driving coils 26. The retarding force and hence, the speed of the motor, that is, of all the motors, can be varied by adjusting 55 the voltage regulator 33. This feature forms no part of this invention. Each bucking coil 25 is connected in the feed circuit to receive full voltage therefrom to completely oppose the driving coils and stop the motor as follows.

60 From feed wire 30, to wire 42, contact 43, relay switch 44, contact 45, wire 46, to a branch circuit 47, which is connected to switch contact 48 forming part of the switch 37, and coacting with the contact 38, but normally separated therefrom, but when engaged therewith, closing the branch circuit through the contact 38, wire 39, bucking coil 25, wires 40 and 41 to the feed wire 31. There is one wire 47, contact 48 for each timer, but one relay switch 44 for all the timers, this being located at the central station 6, but normally as

the contacts 48 are separated from the contacts 38, the full voltage is cut out of the bucking coils of all the motors. The bucking coils 25 are cut into the full voltage circuit by the timer, as will be hereinafter described. It will be noted that the switch contacts 48 of all the timers are connected in multiple in the feed circuit and hence, the contact 48 of any one timer when it is engaged with the contact 38 of that timer will cause the bucking coils to be fully energized and stop the companion motor independently of the stopping of the other motors.

The means for restarting all the motors simultaneously comprises a series resynchronizing circuit circuit including normally separated switch contacts 50, 51 forming part of each switch 37, these being connected to the coil 52 of a relay circuit which operates the relay switch 44 to separate it from the contacts 43, 45, and move it into position to close a stick relay circuit and timed means, as a normally closed switch in the stick relay circuit and operable to open the stick circuit after it has been closed a predetermined period or a period long enough to permit all the timers to get under way, that is permit 100 all of the arms 18 of the timer to clear or ratchet past the parts 15. The switch in the stick circuit being timed as by heating coils or their equivalents connected in the stick circuit so as to be heated when the stick circuit closes, the heating 105 requiring a predetermined time before the switch is heated sufficiently to be opened by the heat of the coils. The synchronizing circuit with the exception of the relay 44, the stick circuit therefor and the timing means or heating coils or their equivalents, per se, form no part of this invention 110 but constitutes the subject matter of my pending application Ser. No. 460,771, filed June 12, 1930. The contacts 50 and 51 are brought together by the operation of the offset arm 18 on 115 the part 15 and hence, the contacts 50 and 51 of the plurality of timers being in series, the coil of the relay circuit can not be actuated until all the timers have completed their cycle and caused their parts 15 to operate the companion switches 120 37.

One end of the coil 52 is connected by a wire 53 to the contact 50 of but one of the timers. The contact 51 is connected by a wire 54 to the contact 50 of the next timer and likewise, the contact 51 of the next timer is connected in series with the contact 50 of a third timer etc., throughout the system of timers, and the contact 51 of the last timer in the series is connected by wire 55 to the feed wire 30. Thus, when all the contacts 50, 51 are engaged, the coils 52 will be energized causing them to operate the relay switch 44, through the core 56 and shift the relay switch 44 into engagement with contacts 57, 58 in the relay circuit, these contacts being connected respectively by wires 59 to the feed wire 30, and by wires 60 and 61, contact 62 to a normally closed switch 63 connected by a wire 64 to the coil 52 completing the stick relay circuit. Thus, when the relay switch 44 is operated out of its normal position by the coil, and the contacts 38 and 48 of all the timers are engaged, the circuit through these contacts 38, 48 will be broken by reason of the relay 44 separating from the contacts 43, 45 and therefore, the full voltage circuit through the bucking coils 25 broken so that the motors are free to start all simultaneously, and the arms 18 will ratchet past the arms 15, and the timers 135 continue on their next cycles.

In order to hold the relay switch 44 engaged 150

with the contacts 57, 58 while the arms 18 are ratcheting past the parts 15, or in other words, to give all the arms 18 time to ratchet past the parts 15, means is provided for holding the stick 5 relay energized independently of the contacts 50, 51, it being borne in mind that as soon as any one arm 18 ratchets past the corresponding part 15, the companion contacts 50, 51 will separate and thus break the circuit through the coil 52 10 of the stick relay circuit.

Therefore, means is provided for holding the stick relay circuit closed when this occurs and for opening it a predetermined period after it occurs, and after all the arms 18 have ratcheted 15 past the parts 15 so that all timers are underway on their next cycles. This means for holding the coil 52 energized is the switch 63, and it is opened after a predetermined period by timed means independent of the timers, and again 20 closed after the relay switch 44 has been turned to its normal position engaged with the contacts 43, 45. This timed means is preferably thermal operated to open the switch 63 under the influence of heat and again close it when cooled, although any other delayed action means may be 25 employed.

70 are heating coils around the switch 63, which switch includes thermostatic metals. One end of the coils is connected by a wire 71 to the wire 30 60 of the stick relay coil circuit, and the other end of the coils by a wire 72 to the common return wire 41. Thus, after the relay switch 44 has been shifted into engagement with the contacts 57, 58 to close the stick relay circuit, this 35 operation being effected by the closing of all the pairs of contacts 50, 51, the heating coils 70 are now connected in a closed circuit and begin to heat up and act on the thermostatic metals of the switch 63. During this heating up period, one 40 or more, but not all of the arms 18 may have ratcheted past their corresponding parts 15, but by the time the heating coils 70 have heated the thermostatic metals sufficiently to cause the switch 63 to open, all arms 18 have ratcheted 45 past their corresponding parts 15, and hence, when the thermostatic switch 63 does open the circuit through the relay coil 52, the relay switch 44 returns to its normal position. The thermal switch 63 then cools and returns to its normal 50 position where it remains until the relay circuit is again closed by all of the pairs of contacts 50, 51 being again engaged. The heating up of the coils sufficiently to affect the thermostatic metals of the switch 63 is not complete until 55 all arms 18 have had time to ratchet past the parts 15.

Each switch 37 in addition to the pairs of contacts 36, 38, 48; 50, 51 includes an additional contact 80 paired with the contact 36 and interposed between the contact 36 and the contact 51. This contact 80 is arranged in a circuit to cut in a resistance 81 to balance or take the place of the bucking coils 25 of any one motor when the bucking coils are cut out of the circuit by the 60 separation of the contacts 36, 38 by the arm 15. This is for the purpose of maintaining the conditions in the circuit including the wire 34 leading from the voltage regulator 33 constant, as the timers are stopped one by one.

70 The terminals 50, 51; 80, 36; 38 and 48 are arranged in a row, or in any other position, so that the separating motion of the terminals 36, 38 is transferred to them. The contacts 36 and 38 are tensioned to engage each other when unrestrained by the parts 15. The other contacts

are tensioned to separate when unrestrained. The contacts 80 and 51 are separated by a piece of insulation 82. The contacts 36 and 38 are formed with extensions which diverge from each other, and the part 15 engages these diverging 80 portions when actuated by the offset arm 18 and thus, separates the contacts 36, 38 to break the normal circuit therethrough, to the bucking coils 25. The separation of the contacts 36, 38 causes the contact 38 to engage the contact 48 and thus, cut the bucking coils 25 into the full voltage circuit to stop the motor. The separating movement of the contact 36 causes it to engage the contact 80 and cut in the corresponding resistance 81, and this movement also imparts 85 sufficient movement to the contact 51 to cause it to engage the contact 50 in order that the coil 52 of the relay will be cut into a closed circuit when the contacts 50 and 51 of all the timers or switches 37 are engaged.

In operation, the motors of all the timers are running at their normal speed with the bucking coils 25 opposing the driving coils 26 with a predetermined resistance, the circuit through the bucking coils being closed through the contacts 36, 38. The amount of current passing through the bucking coils and hence, the speed of the motors is controlled by the setting of the regulator 33. The speed of the motor determines the extent of the traffic cycle of the signals controlled by the cams on the timer shaft 100 13. This traffic cycle period may be adjusted for 60, 70, 80, 90, 100 etc., seconds. The motors may not run exactly at the same rate owing to different conditions inherent in the motors, or 105 the coils may be wound so that a particular one runs slower than the other. Toward the end of the traffic cycle, the offset arms 18 begin to engage the corresponding parts 15 depressing said parts to separate the terminals 36, 38 of the companion switches 37 and thus engage the terminals 38 and 48 to cut in full voltage current through the bucking coils of the companion motor and stop the motor and the timer, and at the same time, the resistance 81 is cut in by the contact 110 80, and the contacts 50 and 51 are engaged. When all of the motors are thus stopped, all the contacts 50 and 51 in the series resynchronizing circuit are engaged thus closing the circuit through the relay coil 52, operating the relay switch into 115 engagement with the contacts 57, 58, thus breaking the circuit through all the bucking coils 25 so that all the motors are free to start without any retarding force. Hence, the timers start, and the arms 18 thereof ratchet past the parts 120 15, thus permitting the contacts of the switches to return to normal position. This may not occur in all the switches 37 at the same time.

The thermal switch breaks the circuit through the stick relay circuit after all the offset arms 18 135 have had time to clear their parts 15 and when the thermal switch 63 opens the stick relay circuit, the relay switch 44 returns to its normal position in engagement with the contacts 43, 45. Hence, all circuits are restored to their normal 140 condition and the timer continues in its cycle until the offset arms 18 again depress the parts 15. The parts 15 are returned to their normal position after the arms 18 ratchet past them by the returning spring 17. When the circuit 145 through the heating coils 70 is thus broken, the coils cool and the switch 63 returns to its normal position in engagement with the contact 62, but in the meantime, the relay switch 44 has returned to its normal position and the circuit through the 150

relay coil 52 has been broken by the separation of the contacts 50, 51. This operation is repeated during each cycle of the timer.

What I claim is:

- 5 1. In a resynchronizing system including a plurality of controllers, each controller comprising a cycle timer and actuating means therefor, means controlled by each timer for stopping the same at the end of its cycle independently of the other timers comprising two parts, one fixed from movement with the timer, and the other movable by the timer into and out of engagement with the former part, timed means controlled by the last stopped timer for starting all the timers simultaneously on their next cycles, and means common to all of the timers for rendering the stopping means ineffective while the movable timer parts are moving out of engagement with the other parts.

20 2. In a resynchronizing system including a plurality of controllers, each controller comprising a cycle timer and actuating means therefor, means controlled by each timer for stopping the same at the end of its cycle independently of the other timers comprising a feed circuit, branch circuits, one for each timer, electrically operated means in each branch circuit for stopping the companion timer, a normally open switch in each branch circuit, two coacting parts for each timer, one fixed from movement with the timer, and the other movable by the timer into and out of engagement with the former part to close the companion switch, and means controlled by the last stopped timer to open all the branch circuits simultaneously.

35 3. In a resynchronizing system including a plurality of controllers, each controller comprising a cycle timer and actuating means therefor, means controlled by each timer for stopping the same at the end of its cycle independently of the other timers comprising a feed circuit, branch circuits, one for each timer, electrically operated means in each branch circuit for stopping the companion timer, a normally open switch in each branch circuit, two coacting parts for each timer, one fixed from movement with the timer, and the other movable by the timer into and out of engagement with the former part to close the companion switch, a resynchronizing circuit having normally open switches in series therein, one for each timer, and closable by the operation of said parts, a normally closed relay switch common to all the branch circuits, electro-magnetic means in the resynchronizing circuit for opening the relay switch when all the switches in the resynchronizing circuit are closed by the timers, a normally open stick relay circuit closable by the opening of the electro-magnetic relay switch, and timed means for opening the stick relay circuit while said parts of all the timers are moving out of engagement with each other.

60 4. In a resynchronizing system including a plurality of controllers, each controller comprising a cycle timer and actuating means therefor, means controlled by each timer for stopping the same at the end of its cycle independently of the other timers comprising a feed circuit, branch circuits, one for each timer, electrically operated means in each branch circuit for stopping the companion timer, a normally open switch in each branch circuit, two coacting parts for each timer, one fixed from movement with the timer, and the other movable by the timer into and out of engagement with the former part to close the companion switch, a resynchronizing circuit having

normally open switches in series therein, one for each timer, and closable by the operation of said parts, a normally closed relay switch common to all the branch circuits, electro-magnetic means in the resynchronizing circuit for opening the relay switch when all the switches in the resynchronizing circuit are closed by the timers, a normally open stick relay circuit closable by the opening of the electro-magnetic relay switch, and means for opening the stick relay circuit while said parts of all the timers are moving out of engagement with each other, the last mentioned means including a normally closed thermostatically operated switch in the stick relay circuit and having its heating coils connected in said stick relay circuit. 90

5. A resynchronizing system including a plurality of controllers, each controller comprising a cycle timer and actuating means therefor, means controlled by each timer for stopping the same at the end of its cycle of movement independently of the other timers comprising a feed circuit having branch circuits, one for each timer, electro-responsive means in each branch for stopping the companion timer, and a normally open switch in each branch, a resynchronizing circuit connected in the feed circuit having normally open switches connected in series therein, one switch for each timer, two coating parts for each timer, one fixed from movement with the timer, and the other movable by the timer into and out of engagement with the former part to close said normally open switch of the companion timer, a normally open stick relay circuit having a normally closed switch therein, a relay switch normally closing the branch circuits and common to all of them and having its coils connected in the synchronizing circuit in series with the normally open switches therein, the relay switch being movable to open the branch circuits when its coils are energized and close the stick relay circuit, and timed means independent of the timers for opening the normally closed switch in the stick relay circuit after said parts have moved out of engagement. 120

6. A resynchronizing system including a plurality of controllers, each controller comprising a cycle timer and actuating means therefor, means controlled by each timer for stopping the same at the end of its cycle movement independently of the other timers comprising a feed circuit having branch circuits, one for each timer, electro-responsive means in each branch for stopping the companion timer, and a normally open switch in each branch, a resynchronizing circuit connected in the feed circuit having normally open switches connected in series, one switch for each timer, two coacting parts for each timer, one fixed from movement with the timer, and the other movable by the timer into and out of engagement with the former part to close said normally open switch of the companion timer, a normally open stick relay circuit, a normally closed switch therein, a relay switch normally closing the branch circuits and common to all of them and having its coils connected in the synchronizing circuit in series with the normally open switches therein, the relay switch being movable when its coils are energized into position to break the branch circuits and close the stick relay circuit, the normally closed switch in the stick relay circuit being a thermal switch having heating coils connected in the stick relay circuit and operating to open the switch when heated, and to close it

when cooled and thereby delaying the breaking of the stick relay circuit until said parts have moved out of engagement on the next cycle of movement of the timers.

- 5 7. In a resynchronizing system including a plurality of controllers, each controller comprising a cycle timer and actuating means therefor, means controlled by each timer for stopping the same at the end of its cycle independently 80
 10 of the other timers, timed means controlled by the last stopped timer for starting all the timers simultaneously on their next cycle comprising a resynchronizing circuit having normally open switches in series therein, one switch for each 85
 15 timer, coacting parts for each timer, one part being fixed relatively to its companion timer, and the other movable thereby into and out of engagement with the former to close the companion switch and stop the timer, and out of engagement with said switch to permit it to open, a relay switch circuit having a relay switch therein, the coils of which are connected in series with said switches in the resynchronizing circuit a normally open stick relay circuit also connected 90
 20 to said coils, the relay switch operating to close the stick relay circuit when its coils are energized, and means for controlling the opening of the stick relay circuit by said relay switch until said parts of the timers have moved out of engagement on the next cycle of movement.

- 30 8. In a resynchronizing system including a plurality of controllers, each controller comprising a cycle timer and actuating means therefor, means controlled by each timer for stopping the same at the end of its cycle independently of the other timers, timed means controlled by the last stopped timer for starting all the timers simultaneously on their next cycle comprising a resynchronizing circuit having normally open 100
 35 switches in series therein, one switch for each timer, coacting parts for each timer, one part being fixed relatively to its companion timer, and the other movable thereby into and out of en- 105
 40 gagement with the former to close the companion switch and stop the timer, and out of engagement with said switch to permit it to open, a relay switch circuit having a relay switch therein, the coils of which are connected in series with said switches in the resynchronizing circuit a normally open stick relay circuit also connected to said coils, the relay switch operating to close the stick relay circuit when its coils are energized, and means for controlling the opening of the stick relay circuit by said relay switch until said parts of the timers have moved out of engagement on the next cycle of movement.

gagement with the former to close the companion switch and stop the timer, and out of engagement with said switch to permit it to open, a relay switch circuit having a relay switch therein, the coils of which are connected in series with said switches in the resynchronizing circuit a normally open stick relay circuit also connected to said coils, the relay switch operating to close the stick relay circuit when its coils are energized, and means for controlling the opening of the stick relay circuit by said relay switch until said parts of the timers have moved out of engagement on the next cycle of movement, the last named means including a thermal switch having its heating coils connected in the stick 90
 95 relay circuit.

9. In a resynchronizing system including a plurality of controllers, each controller comprising a cycle timer and actuating means therefor, brake means controlled by each timer for applying a braking force to stop the same at the end of its cycle independently of the other timers, timed means controlled by the last stopped timer and operable to release the braking force of all the brake means simultaneously and means for 100 rendering said brake means inoperative for a predetermined length of time after the braking force has been released.

10. In a resynchronizing system including a plurality of controllers, each controller comprising a cycle timer and actuating means therefor, brake means controlled by each timer for applying a braking force to stop the same at the end of its cycle independently of the other timers, timed means controlled by the last 110 stopped timer and operable for releasing the braking force of all the brake means simultaneously and means common to all the timers for rendering the brake means ineffective until all the timers have passed through a predetermined 115 portion of their cycle.
